His Attorney.

UNITED STATES PATENT OFFICE

2,198,480

TABLE

Charles A. Lindemann, Bridgeport, Conn., assignor to General Electric Company, a corporation of New York

Application July 19, 1939, Serial No. 285,290

3 Claims. (Cl. 45—68)

The present invention relates to tables equipped with a box cover for enclosing the top of the table.

The object of my invention is to provide an improved construction and arrangement for supporting the cover so that it may be swung from a position enclosing the table top to a position at the end of the table, providing an auxiliary table surface.

10 For a consideration of what I believe novel and my invention, attention is directed to the following description and the claims appended thereto.

In the accompanying drawing, Fig. 1 is a perspective view of a table embodying my invention with the cover in the closed position; Fig. 2 is an end elevation partly broken away to show the hinge construction, the cover being in the closed position; Fig. 3 is a perspective view of the table, 20 the cover being in the open position; Fig. 4 is an end elevation of the table and cover in the position of Fig. 3 broken away to show the hinge construction and the manner of mounting the supporting legs in the cover; and Fig. 5 is a 25 fragmentary top plan view of the table and the adjacent end of the cover, the cover being in the open position.

Referring to the drawing, there is shown a sheet metal table having a top 1 provided with 30 downwardly extending flanges 2 and 3 respectively at the sides and ends. In the corners of the table top are secured angle-shaped supporting legs 4.

The table provides a support for a rotary ironer 35 comprising a roll 5, and a shoe 6 supported by a frame 7 containing the operating mechanism for the ironer. The frame is suitably mounted on the table top. The ironer is typical of devices which may be supported on the table top.

40 The ironer is enclosed by a box cover having a top wall 8, and depending side walls 9 and end walls 10. In the closed position the edges of the side and end walls are presented to the table top and provide an enclosure for the ironer.

45 At the right-hand end of the table is a vertical hinge member 11 having its lower end pivoted on a pin 12 mounted between ears 13 of a bracket 14 secured to a brace 15 extending between the legs 4. The upper end of the hinge member 11 is pivoted in ears 16 of a bracket 17 connected to the adjacent end wall 10 of the cover. The connection between the hinge member and the end wall of the cover comprises a pin 18 extending through a reenforcing strap 19 secured to the inner surface of the cover end wall. The cover

is pivoted on the pin 18 and is held thereon by a washer 20 arranged between the inner surface of the reenforcing strap 19 and a cotter pin 21 extending through the pin 18.

The steps in moving the cover from the closed 5 to the open position are shown in Figs. 1 and 3. The cover is first moved from the full-line to the dotted-line position of Fig. 1 by movement of the hinge member 11 from the vertical to the horizontal position about the pin 12. Upon reaching the horizontal position the inner end of the hinge member 11 engages a stop 22 integral with the bracket 14 which holds the hinge member 11 in the horizontal position. Since the pin 12 is perpendicular to the front of the table top, 15 the hinge member and cover are moved to the dotted-line position of Fig. 1 by pivotal movement about an axis perpendicular to the front of the table top. In this position the side and end walls of the cover are presented toward the end 20 of the table top. In the next step the cover is pivoted from the position shown in dotted lines in Fig. 1 to the position shown in dotted lines in Fig. 3. In the position shown in Fig. 3 the side and end walls of the cover are presented toward the front of the table top. During this movement the cover pivots on the pin 18 and the pivotal movement is about a vertical perpendicular to the end wall of the cover. In moving to the dotted-line position of Fig. 3 the rear side 25 wall of the cover is moved to a position adjacent the end of the table top. To reach the final open position shown in full lines in Fig. 3 the cover is swung downward about the pivot provided by the ears 16 on the hinge member 11. This pivotal 30 movement is about a horizontal axis perpendicular to the side walls of the cover. Upon reaching the final open position the cover is at one end of the table top with its top wall 8 uppermost providing an auxiliary table surface. In this position the cover is supported by a stop 23 fixed to the front table leg and engaging the lower edge of the cover top, and by legs 24 and 25 at the front end of the cover. The stop 23, as shown in Fig. 5, limits the pivotal movement of the cover 35 about the pin 18 and about the hinge member 11. The legs 24 and 25 provide a stable support for the front end. The leg 24 is pivoted at 26 on the inner surface of the cover end wall 10 and can be swung up within the cover as shown in 40 dotted lines in Fig. 4. The leg 25 is similarly pivoted at 27 on the rear side wall of the cover and may be similarly swung up within the cover.

In the present construction the top wall 8 of the cover in the open position is level with the 45

table top. By changing the length of the hinge member 11 and the position of the connections thereto the height of the top wall of the cover in the open position may be lower or higher than the table top.

5 What I claim as new and desire to secure by Letters Patent of the United States is:

1. In combination, a support, a box-like cover for enclosing the top of the support having a top wall and having depending side and end walls presented toward the support, a hinge member at one end of the support pivoted thereon for pivotal movement on an axis perpendicular to the front of the support, a pivotal connection between the hinge member and the adjacent end of the cover whereby the cover may be swung by pivotal movement of the hinge member to a vertical position with its side and end walls presented toward the end of the support and may thereafter be pivoted about an axis perpendicular to the end of the cover to a position in which the side and end walls are presented toward the front of the support, and means pivoting the cover on the support for swinging movement from said vertical position downward to a horizontal position about an axis perpendicular to the end of the support.
- 10 2. In combination, a support, a box-like cover for enclosing the top of the support having a top wall and having depending side and end walls presented toward the support, a vertical hinge member pivoted thereon at its lower end for piv-

15 otal movement to a horizontal position about an axis perpendicular to the front of the support, and pivotal connections between the upper end of the hinge member and the adjacent end of the cover connecting the cover to the hinge member for swinging movement therewith and providing for pivotal movement of the cover on the hinge member about axes respectively perpendicular to an end wall and to a side wall of the cover.

- 20 3. In combination, a support, a box-like cover for enclosing the top of the support having a top wall and having depending side and end walls presented toward the support, a hinge member at one end of the support pivoted thereon for pivotal movement on an axis perpendicular to the front of the support, a pivotal connection between the hinge member and the adjacent end of the cover whereby the cover may be swung by pivotal movement of the hinge member to a vertical position with its side and end walls presented toward the end of the support and may thereafter be pivoted about an axis perpendicular to the end of the cover to a position in which the side and end walls are presented toward the front of the support, means pivoting the cover on the support for swinging movement from said vertical position downward to a horizontal position about an axis perpendicular to the end of the support, and a stop on the support for holding the top wall of the cover in a horizontal position.

39 CHARLES A. LINDEMANN.
